Claims priority, application Netherlands Oct. 21, 1959
1 Claim. (Cl. 28—32)

This invention relates generally to the winding and reeling art and more particularly to the beaming of warps formed from a plurality of separate ends of thread or yarn.

In the practice of the present invention, a plurality of pre-beams are formed, each from a small number of thread ends. Afterwards, the pre-beams are unwound, and the unwound thread from each pre-beam is guided through a reed with vertical reed rods before being rewound onto larger warp beams. The threads originating from each pre-beam accordingly pass in mutually separated planes through the reed. Such a system is generally known, and is used to simplify the so-called warping of especially large warp beams.

If in fact the number of threads to be collected on a warp beam becomes high, then a corresponding increase of the warping creel size is necessary. The number of thread ends required under present manufacturing conditions has become so high that the creel dimensions are exceedingly large. A large warping creel of course requires a large operating space and, additionally, it means that there are great differences in the paths of travel for the various threads. This in turn results in a great difference in tension between these various threads.

These disadvantages are removed by applying a pre-beaming method indicated hereinabove as generally known. With this method, pre-beams having considerably less thread ends are wound from creels with practical dimensions, and thereafter, the pre-beams are together rewound into a warp beam. This known system, however, also has disadvantages.

Thread entanglement easily occurs with this system, however, since the threads are passed in a plurality of planes through the horizontally-mounted reed, normally a separate plane for each pre-beam. Such entanglement gives rise to ruptures of threads or of filaments. If the ruptures occur before the thread reaches the reed, as practically always appears to be the case, the ruptured thread or filaments may be attached to and taken along by other threads, and may be passed through an adjacent reed opening onto the warp beam. As a result, warp beams are obtained with incorrect numbers of threads and/or with threads having variations in denier.

It should be noted that this entanglement also occurs when warping a single web of threads through a reed, although not to such a high degree as when warping from a plurality of pre-beams each of which presents an independent web of threads. The possibility of entanglement in this instance remains restricted to one direction only in contrast to what occurs in the pre-beaming system.

Solutions have been proposed for obviating the pre-beaming thread entanglement problem herein under consideration. It has already been proposed, for example, that a rake-shaped member with extremely flexible teeth be moved over the thread web in a direction perpendicular to the direction of thread travel and parallel to the web, the rake-shaped member being mounted parallel to the reed. In this system, the threads are plucked by the flexible teeth in the manner of strings on a stringed musical instrument, which results in such a vibrating

2

transverse movement of the threads that they remain free from each other.

A similar result has previously been obtained by the use of a rake-shaped member of which the teeth are not necessarily flexible, but have such a short and gradually receding profile that the thread may also be plucked. All these and similar solutions cannot be applied when guiding a multiplex web of threads through a reed as in the case of the aforesaid pre-beaming operation, since it is not possible to pluck all the threads in the various planes within which they are arranged.

It is an object of this invention to provide a warping system not having the many disadvantages of heretofore-known beaming operations.

Another object of the present invention is to provide a thread winding apparatus capable of handling a plurality of webs of thread fed from a plurality of pre-beams without thread entanglement.

Still another object of this invention is to provide a warping process which can be practiced on various beaming or winding machines without the heretofore-resulting entanglement of thread.

The foregoing objects may be accomplished, in accordance with this invention, if a periodically recurring tapping or sharp vibrating movement in a lateral direction is imparted to the webs of thread at a point adjacent to and preferably beyond the guide reel from the pre-beams.

Although the velocity of this tapping movement is not necessarily critical, it has been found that too rapid a movement requires a very extensive operating apparatus. With too slow a movement, however, there is a risk that the web or webs of threads become immobile in between periodic tapping movements to such an extent that thread entanglements again result. None of these disadvantages occur if, according to the present invention, the tapping movement is carried out with a frequency of 1 to 5, and preferably 2 to 3, taps per second.

Moreover, although the tapping of the web of threads may always be done in one direction only, for example, vertically, it is also conceivable to tap the threads in separate planes independent of each other. A simple, but very effective, method appears to consist in a tapping movement effected alternately downwardly and upwardly and in such a manner that during each movement the threads are first pressed together in one plane and then are moved together in a transverse direction. In carrying out the method in this manner, only one tapping member is required for the downward movement and only one for the upward movement.

It is surprising that, although all threads are compressed into one plane, there does not occur thread entanglement. As a matter of fact, this undesirable result is effectively prevented. It would normally be expected that forced pressing together of the threads would entail a higher probability that said threads would be wrapped around each other, and intermingled, and thus stuck together in an inextricable manner. It also seems normal to assume that it does not make any difference if the tapping movement is carried out before or after passage of the threads through the reed. Although it is true that in both cases a distinct decrease in the number of thread ruptures is noticeable, according to the invention it has nevertheless been found that the best results are obtained if the tapping movement is carried out at the side of the reed facing the warp beam, or after the webs pass through the reed.

In addition to the methods described hereinabove, the invention also relates to an apparatus for winding warp beams from pre-beams. The apparatus is comprised of a combined holder/driving device for a warp beam, a

frame for parallel mounting of the pre-beams, as well as a reed having vertical reed rods between the warp beam holder and the frame. A simple construction for enabling periodic tapping movement on the running mass of threads in this apparatus consists in a system of horizontal rods provided near the reed, in which system the rods are arranged vertically above each other and which rods are coupled to an actuating mechanism for giving the system a periodic vertical movement.

The aforesaid actuating mechanism may consist of rods each of which is separately coupled to the actuating mechanism and in which there is one rod for each separate plane of threads. Moreover, the periodic vertical movement of the rods may be chosen very differently, varying from a high frequency vibration with a very short stroke to a slow up-and-down movement with a large stroke. It has been found, however, that a very satisfactory result is obtained with an exceptionally simple apparatus if the system comprises two horizontal rods forming opposite sides of a rectangular frame having the same width as the reed and in which the distance between rods is of the same magnitude as the length of the reed rods, and in which the vertical stroke of the actuating mechanism is also of the same magnitude as the reed rod length. The rectangular frame may be moved up and down in its entirety by the actuating mechanism at a rather quiet rate of 1 to 5 and preferably 2 to 3 strokes per second.

Finally, advantages have been found to result in warp beams wound according to any one of the above-described systems. These warp beams not only appear to have less faults, but are on the whole more uniformly wound. This is particularly noticeable when unwinding said warp beams, the running-off threads showing less mutual differences in running-off tension, which directly contributes to a more uniform fabric upon weaving. It should be noted in this respect that differences in tension between threads running from a warp beam are very easily recognized in the form of pulling threads, glossy threads, and other forms of warp streakiness.

Other objects and advantages of this invention will become apparent upon study of the following detailed disclosure taken in conjunction with the accompanying drawings, wherein

FIGURE 1 is a longitudinal view in elevation of a beaming apparatus constructed according to this invention; and

FIGURE 2 is a detailed front elevational view of the tapping rod system and the actuating mechanism therefor.

In FIGURE 1, reference numeral 1 denotes a warp beam which may be supported and rotated in the direction indicated by the arrow by any conventional means, not shown. Upon rotation of beam 1, the mat 2 of threads is wound thereon over the entire width thereof. Mat 2 is formed out of several webs 3 of thread running in substantially horizontal planes.

Each of said thread webs 3 is unwound from one of an equal number of pre-beams 4. Instead of the six pre-beams 4 shown for the sake of simplicity, a different number may be mounted in a corresponding manner in two planes without the necessity of changing anything essential in the apparatus disclosed. From each pre-beam 4, there runs a thread web 3 which is guided over a freely-rotatable roller 5.

In order to have the threads run in a tensioned condition, the pre-beams are somewhat braked by means of rope brakes 6 known in this art. Said brakes 6 comprise rope laid over a side flange of the pre-beam and held tight by means of a weight. To simplify the drawings, only a single rope brake 6 is shown on the pre-beam 4 appearing at the extreme upper right.

The thread webs 3 running in spaced and somewhat parallel planes are kept separate from each other by means of horizontal dividing rods 7. The dividing rods

7 are loosely laid in a rack 8 provided with securing hooks, as is known. The threads run from said rods 7 through the openings of a reed 9 placed in a horizontal position and transverse to the plane of the drawing. Said reed contains at least as many vertical reed openings as the number of threads on each of the pre-beams 4.

After passing the reed 9, the threads run between the horizontal rods of the tapping system 10 and to the triplet formed by the idler rollers 11, 12, and 13. The tapping system can be moved in a vertical sense up and down according to the arrow indication in FIGURE 1. All of the rollers 11, 12, and 13 are driven by the threads, and rollers 11 and 12 rotate about a fixed axis, whereas the roller 13 is a jockey or dancer roller and, therefore, can move up and down. The jockey roller 13 is supported in its movement by spring 14. Due to the possibility of small vertical movement in said roller 13, the fluctuations in tension in the thread mat 2 are restricted to a minimum.

The tapping system 10 is specifically shown in FIGURE 2 by a front view on an enlarged scale. This system consists in two horizontal rods 15 and 16, formed from anodized aluminum and combined into one body by means of the U-shaped rod 17. Guiding rods 18 and 19, which are connected to said rod 17, permit controlled vertical movement in stationary guides 20 and 21.

The drive for tapping system 10 is produced by the eccentric cam mechanism 22 of a known form. Said mechanism 22 is coupled to the rod 17 by means of the hinge 23 and the entire system may be reciprocated merely by providing rotation to the eccentric with any suitable drive means.

The vertical stroke of the tapping system should be sufficiently long that the rods 15 and 16 will first completely compress the thread mat and then may move the same in a compressed condition up and down as a unit. The distance between the rods 15 and 16 should slightly exceed the normal distance between the upper and the lower threads of the webs 3. The rate at which the tapping system vibrates in the embodiment illustrated amounts to 3 strokes per second.

It has been found that the number of thread ruptures and faults on the warp beams diminished considerably after putting into use the herein-described apparatus provided with a tapping system. It was found that the warp beams thus wound were judged very favorably by the users also with respect to the running-off and processing properties.

As already explained above, it is preferred, in accordance with this invention, to mount the system of horizontal rods at the side of the reed facing the warp beam holder. Although the horizontal rods may be manufactured from various materials such as stainless steel or a ceramic material, the minimum tension shocks and tension variations in the running threads are obtained when the rods are manufactured from anodized aluminum.

The periodic drive for the rod system may also be carried out in various manners. Possible embodiments comprise an electromagnet which is periodically energized, or a hydraulic or pneumatic piston system of known constructions. An especially simple and nevertheless efficient drive has, however, been found to be an actuating mechanism comprising an eccentric or cam which is coupled to a continuously driven shaft.

Inasmuch as other alternatives and modifications within the scope of this disclosure will become apparent to those skilled in this art, it is intended that the present invention be limited only to the extent set forth in the following claim.

What is claimed is:

In an apparatus for winding a plurality of thread webs into a single package comprising a warp beam, a plurality of pre-beams for supplying thread webs to said warp beams, and means for combining the webs into a

single warp while maintaining the individual ends separated, the combination of means for vibrating all of the thread ends prior to collection on said warp beam and means for restricting fluctuations in tension in the threads during their passage between said vibrating means and said warp beam.
